(57) **CLAIM**

The ornamental design for a spa, as shown and described.

DESCRIPTION

FIG. 1 is a top, front, left perspective view of the spa, in accordance with an embodiment;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a top, back, right perspective view thereof.

The broken lines portions are for the purposes of illustrating portions of the spa that form no part of the claimed design.

1 Claim, 7 Drawing Sheets
